UNITED STATES PATENT OFFICE.

ROSWELL A. WHITNEY, OF LOS ANGELES, CALIFORNIA, ASSIGNOR TO OLSTON ELECTRIC COMPANY, OF LOS ANGELES, CALIFORNIA, A CORPORATION OF CALIFORNIA.

DESIGN FOR AN ELECTRIC STOVE.

46,239.

Specification for Design.

Patented Aug. 4, 1914.

Application filed June 3, 1914. Serial No. 842,772. Term of patent 14 years.

To all whom it may concern:

Be it known that I, Roswell A. Whitney, a citizen of the United States, residing at Los Angeles, in the county of Los Angeles, State of California, have invented a new, original, and ornamental Design for Electric Stoves, of which the following is a specification, reference being had to the accompanying drawing, forming part thereof.

The figure is a perspective view of an electric stove, showing my new design.

I claim:

The ornamental design for an electric stove as shown.

ROSWELL A. WHITNEY.
